CHUCK AND GRINDING WHEEL

Charles E. Hite, Philadelphia, Pa., assignor to
Lewis J. Musser, Newtown, Pa.

Application May 23, 1940, Serial No. 336,877

4 Claims. (Cl. 51—209)

The present invention relates to chucks for holding wheels and disks and that more usually are intended for holding grinding wheels and disks when operating upon the wheels and disks in manufacture and subsequently when using them selectively for grinding or facing operations, and the invention relates to wheels and disks, particularly with respect to the mounting portions thereof that cooperate with chuck structures, the invention being in part divisional from the applicant's application for Centrifugal chuck, Serial No. 231,174, filed September 22, 1938, and allowed January 29, 1940.

The terms "wheel" and "grinding wheel" as used herein are intended to apply broadly not only to disk grinding wheels, cup and cone grinding wheels, and facing and sanding plates but also to any similar device adapted to be held by the mechanism of the present invention.

A purpose of the invention is to grip a grinding wheel or wheel mount centrifugally when rotation starts.

A further purpose is to adapt holding jaws having a small range of radial movement to use with wheels over a relatively wide range of sizes.

A further purpose is to accommodate the character of engagement between a jaw and a wheel gripped by the jaw to the needs of service. Thus, when used for holding wheels on a machine for facing and trimming wheels the torsion upon the gripped wheels is much less and much more uniform than when the wheel itself is in grinding service for which reason in the one case the jaw surface presented to the wheel may be either arcuate to fit the wheel curvature or flat to engage the wheel tangentially while in the other case I may provide a radial interlocking of the jaw and wheel, for example, the jaws may present pins into sockets of the wheel or vice versa, and particularly in the case of cup and cone wheels I may provide the wheel and jaws with reversely flaring engagement surfaces, a downward flare of the jaw ends fitting against an upward flare of the wheel.

A further purpose is to grip a cylindrical cup wheel having a downwardly flaring base with jaw surfaces flaring upwardly to fit the downward flare of the base.

A further purpose is to form a cylindrical cup wheel with a downwardly flaring base for presentation to upwardly flaring jaw surfaces of preferably centrifugally operated chuck jaws.

A further purpose is to provide a bi-part metal base for use with cone cup wheels converging downwardly, flaring the upper part of the base upwardly to fit the interior conical surface of the

wheel, preferably flaring the lower part of the base downwardly for engagement by correspondingly upwardly overhanging jaw surfaces, and clamping the wheel to its base in removably fastening the base parts together.

Further purposes will appear in the specification and in the claims.

I have elected to illustrate a number only out of the many forms of my invention, selecting forms however that are practical and efficient in operation and which well illustrate the principles involved.

Figures 1 and 2, in broken top plan and broken sectional elevation respectively, are intended to illustrate conventionally mechanism embodying the present invention and to show a wheel or wheel mount held by a plurality of chuck jaws (three in the figures) of any suitable form and gripping by the centrifugal action of any suitable mechanism within the body of the chuck. Figure 2 is a section of Figure 1, on the line 2—2 thereof.

Figures 3, 4 and 5 are fragmentary sectional elevations intended to illustrate somewhat different arrangements at the wheel and jaw with somewhat different types of wheel, in each case the jaw being intended to operate centrifugally in any suitable way, optionally as in Figure 2 with minor structural changes.

Figure 6 is a fragment left elevation of Figure 2.

Like numerals refer to like parts in all figures. Describing in illustration and not in limitation and referring to the drawing:

In Figures 1 and 2, a wheel 15 on a three-part base 46, 47, 48 is held by the jaws 16 of a chuck 17 upon a spindle 18 of any suitable machine beyond the spindle, the jaws radially gripping and longitudinally overlapping the wheel. This machine may be, for example, one for facing and trimming unfinished wheels, or it may be a grinding machine for using different wheels selectively for grinding, or it may be any mechanism for suitably rotating the spindle.

An operator using my chuck on a machine for facing and trimming unfinished wheels normally operates upon wheels of different standard commercial sizes, first upon a succession of wheels of one size, then upon a succession of wheels of another size, and so on with wheels of other sizes, changing the wheel each time rotation ceases and at intervals changing the setting of the chuck to accommodate a different size (diameter) of wheel.

With my chuck on a grinding machine, an operator with some classes of work may not change

the wheel over many periods of rotation and in other classes of work selects his wheel to suit the work, often using one wheel for initial rough grinding, with all of the wheels probably more usually being of the same commercial size but sometimes of different sizes, particularly if the spindle 18 is to operate selectively at different speeds or if the chuck is to be used selectively on different spindles of different speeds.

When the chuck is rotating centrifugal action of mechanism within the chuck causes that mechanism to press the jaws radially inward upon the wheel or wheel base, gripping the wheel by the centrifugal action of the mechanism within the chuck.

When rotation of the chuck stops the centrifugal action also stops and I intend the grip of the jaws upon the wheel or wheel base then selectively automatically to release or, under the action of jaw-holding mechanism, to maintain until the operator releases the jaw-holding mechanism.

When the operation is to be with a succession of wheels, as one wheel 15 during each period of rotation and a different wheel 15 during the next period of rotation, I intend the jaws to release and open automatically as the rotation stops, and the degree of opening preferably then to be merely that permitting an easy and rapid change of wheels.

Each time rotation starts after changing one wheel for another the somewhat retracted jaws 16 move inward coordinately upon the inserted wheel 15, centering it and gripping it at its base 48.

When the chuck is to hold a wheel for heavy duty grinding I may provide a pin-and-socket interlocking between the wheel and each jaw, for example, as indicated in Figure 5, where each jaw 16 presents a metal pin 41 into a socket 42 formed in the wheel 15. This pin-and-socket interlocking of the wheel and chuck jaws eliminates any danger of rotational slippage between the wheel and chuck during heavy duty service and greatly lessens the needs for gripping engagement between the wheel and chuck during periods of non-rotation; this is particularly true in that I provide means for limiting the degree of jaw opening to any desired value that optionally may be made substantially zero.

More usually any pin-and-socket interlocking of the wheel and chuck jaws is unnecessary in that I may dimension the parts to secure any desired gripping of the jaws upon the wheel, but the pin-and-socket interlocking may become desirable when the wheels are to be used in non-horizontal positions, particularly if the wheels are cylindrical or cone cup wheels and are to be subjected to heavy stresses tending to pull the wheel both axially and laterally away from the chuck.

I intend to provide a cylindrical cup wheel, such as 43, Figure 4, with a base portion 44 having an outside downward flare and to provide chuck jaws 16³ with a corresponding upward and inward flare, an inwardly directed overhanging portion 45, to fit the downward and outward slope of the base.

In Figure 3 I show a cup wheel 43 having a base 44 inwardly converging downward and for each size of this type of wheel I provide a three-part base, a lower part 46 adapted to be held by the jaw 16 of my chuck, an upper part 47 fitting the interior of the converging base 44 of the cup wheel at a portion thereof slightly above

the base 46 and a central screw 48 removably clamping the upper and lower parts and cup wheel together. As shown the screw 48 has a downward extension 49 of reduced diameter into the center bore 40 of the chuck.

It will be seen that each cup wheel may be used up in service down to the upper part 47 of my composite base and that the stub may be then taken off the base by unscrewing the screw 48 and a new cup wheel of the same interior size then mounted on the composite base in place of the used up wheel. In Figure 3 the chuck jaw 16 presents a somewhat overhanging surface at 45² to the somewhat downwardly outwardly sloping periphery of the base 46.

In Figures 1 and 2 a cone cup wheel 15 is shown mounted upon my composite base, the upper part 47 fitting the interior of the cup wheel a little above the base 46 and cooperatively with the screw 48 clamping the wheel to the lower base 46, with the reduced end 49 of the screw centering the composite base and wheel in fitting into the center bore 40 of the chuck. The lower part 46 of the composite base and the chuck jaws present suitable longitudinally interlocking surfaces one to the other, an overhanging jaw surface 45² engaging the corresponding downwardly flaring periphery of the base part 46.

Whenever my chuck is intended to be used exclusively with cup or other wheels intended to be mounted in service upon a base having a centering pin 49 or 49¹ in a center bore 40 or 40¹ of the chuck, other means for equalizing the radial movements of the different jaws optionally may be omitted.

In the structure of Figures 1 and 2 the jaws are radial slides, each jaw 16 sliding in a radial inverted T slot with lateral runners of the jaws sliding in lateral runway portions of the slot. On its under side the jaw is provided with a succession of upward recesses 69 to receive selectively the upper end of an operating bolt or pin 56 presented from a centrifugally operated hub 83 and adapted to be pulled downward into the hub out of the recess to permit shifting of the jaw to receive the operating pin 56 selectively in any of the recesses 69.

Each operating member of a jaw includes the pin 56 and an integral diametral slide comprising the hub 83 carrying the pin 56, a weight 57 diametrically opposite the hub 83 and a web or plate 84, 85 or 86 connecting the weight and hub and centrally slotted at 87 to pass the hub 83 of the chuck.

The pin 56 is illustrated as maintained in its operating position by a flat spring 70, one carried by each of the plates 84, 85 and 86, with minor modification of the mountings to best adapt it to the somewhat different locations of the plates.

As shown, the end of the spring 70 underlaps a shoulder 104 of the pin 56. When it is desired to change the setting of the jaws the pins 56 are pulled downward by a suitable tool after which the jaws are slid to the desired setting.

Each weight 57 is provided with an upward lug 90 within a radial guideway slot 91 of the chuck body and at the diametrically opposite side of the chuck the hub 83 slides in a radial guideway 92, and the operating mechanisms of the different jaws, as illustrated, are intended to differ merely in the location of the plates 84, 85 and 86 with respect to the hub and weight members 83 and 57 at their diametrically opposite

ends, the plates 84, 85 and 86, angularly spaced 120 degrees being located successively one above and against another.

Each weight 57 is provided with a cam slot 107 which receives the upwardly projecting end of a pin 108 rigidly mounted in a retraction plate 109, the lower end of the pin 108 extending downwardly to adjustably limit the retraction, the opening movement of the chuck, by engaging a cam edge 110 of a stop plate 111 angularly adjustable on the hub 59 of the chuck.

A torsion spring 112 surrounding the hub 59 has its ends 113 and 114 extending into the hub 59 and the retraction plate 109 respectively, the resulting torsion on the plate being in direction to pull the weights 57 radially inward by means of the upper end of the pins 108 in the cam slot 107 of the respective weights, thereby retracting the jaws outwardly.

The screw 100 has a taper body at 115 adapted to clamp against the sloping edges 116 of a slot 101 in the hub 99 of the stop plate 111, thereby permitting peripheral adjustment of the plate upon loosening this screw, shifting the plate to the desired position and then retightening the screw, to adjustably set the retraction of the chuck jaws. A collar 117 fastened to the hub 59 cooperatively with the torsion plate 109 and the stop plate 111 at the set screw 100 may conveniently carry the weight of the operating mechanism.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention what I claim as new and desire to secure by Letters Patent is:

1. A chuck for holding a grinding wheel having a frusto-conical upwardly converging base and the chuck comprising a chuck body, weight means mounted in said body adapted to move outwardly with respect to the axis of the said body under the influence of centrifugal force when the chuck is rotated, jaws having upwardly converging inward surfaces presented to the upwardly converging base adapted to clamp the base upon the body, means connecting said weight means and said jaws in such manner as to cause the jaws to move inwardly toward the axis of the chuck as the weight moves outwardly away from said axis and thereby clamp a wheel base placed between the jaws.

2. A cup wheel interiorly converging downwardly near its lower end, a frusto-conical upwardly converging base under the wheel and co-

axial therewith, a disk inside the wheel near the lower end of the wheel fitting the downwardly converging wheel interior and a screw engaging the disk and base to hold the base, the wheel, the disk and the screw coaxial in a rigid unit for cooperative use with a wheel chuck comprising a chuck body, weight means mounted in the body adapted to move outwardly with respect to the axis of the body under the influence of centrifugal force when the chuck is rotated, jaws having upwardly converging inward surfaces adapted to clamp the base upon the body and means connecting said weight means and said jaws in such manner as to cause the jaws to move inwardly toward the axis of the chuck as the weight moves outwardly away from said axis and thereby clamp a wheel base placed between the jaws.

3. A frusto-conical upwardly converging base for use under a cup wheel having an interior converging downwardly near its lower end, a disk to fit inside the wheel in the converging portion and a screw engaging the disk and base to hold the base, the wheel, the disk and screw coaxial in a rigid unit for use with a wheel chuck comprising a chuck body, weight means mounted in said body adapted to move outwardly with respect to the axis of the body under the influence of centrifugal force when the chuck is rotated, jaws having upwardly converging inward surfaces presented to the upwardly converging base to clamp the base upon the body, means connecting said weight means and said jaws in such manner as to cause the jaws to move inwardly toward the axis of the chuck as the weight moves outwardly away from said axis and thereby clamp a wheel base placed between the jaws.

4. A frusto-conical converging base for use under a cup wheel having an interior converging downwardly near its lower end, a disk to fit inside the wheel in the converging portion, a screw engaging the disk and base to hold the base, the wheel, the disk and the screw coaxial in a rigid unit for cooperative use with a wheel chuck, the screw having a downward extension for registry in a center bore of the chuck and the chuck comprising a chuck body, weight means mounted in said body adapted to move outwardly with respect to the axis of the said body under the influence of centrifugal force when the chuck is rotated, jaws having upwardly converging inward surfaces presented to the upwardly converging base adapted to clamp the base upon the body, means connecting said weight means and said jaws in such manner as to cause the jaws to move inwardly toward the axis of the chuck as the weight moves outwardly away from said axis and thereby clamp a wheel base placed between the jaws.

CHARLES E. HITE.
